INVENTOR

James F. Dobbins.

BY

J. H. Thompson

HIS ATTORNEY.

UNITED STATES PATENT OFFICE.

JAMES F. DOBBINS, OF BROOKLYN, NEW YORK.

DESIGN FOR A COMBINED PEPPER, SALT, AND NAPKIN HOLDER.

54,393.

Specification for Design.

Patented Feb. 10, 1920.

Application filed November 21, 1918. Serial No. 263,628. Term of patent 7 years.

To all whom it may concern:

Be it known that I, JAMES F. DOBBINS, a citizen of the United States of America, residing at 344 Jay street, Brooklyn, in the county of Kings and State of New York, have invented a certain new and ornamental Design for a Combined Pepper, Salt, and Napkin Holder, of which the following is a specification.

The figure is a front perspective view of the combined pepper, salt, and napkin holder.

I claim:—

The ornamental design for a combined pepper, salt, and napkin holder as shown and described.

In testimony whereof I have affixed my signature.

JAMES F. DOBBINS.
